CLAIM

The ornamental design for an inflatable chair, as shown and described.

DESCRIPTION

FIG. 1 is perspective view of the inflatable chair of the present invention;

FIG. 2 is a front elevation view of the inflatable chair of the present invention;

FIG. 3 is a rear elevation view of the inflatable chair of the present invention;

FIG. 4 is a left side elevation view of the inflatable chair of the present invention;

FIG. 5 is a right side elevation view of the inflatable chair of the present invention;

FIG. 6 is a top plan view of the inflatable chair of the present invention;

FIG. 7 is a bottom plan view of the inflatable chair of the present invention;

FIG. 8 is a perspective view of a second embodiment of the inflatable chair of the present invention;

FIG. 9 is a perspective view of a third embodiment of the inflatable chair of the present invention;

FIG. 10 is a perspective view of a fourth embodiment of the inflatable chair of the present invention; and,

FIG. 11 is a perspective view of a fifth embodiment of the inflatable chair of the present invention.

The ornamental design which is claimed is shown in solid lines in the drawings. Any broken lines in the drawings are for illustrative purposes only and form no part of the claimed design.
